To all whom it may concern:

Be it known that I, LOUIS HORNBERGER, a citizen of the United States, residing at Bridgeport, Fairfield county, Connecticut, have invented a new Design for Vases for Lamps and the Like, of which the following is a specification.

The accompanying drawing represents my vase in perspective.

The invention relates to a design for a vase adapted to lamps and similar articles; and the design consists in the configuration and ornamentation thereof, as shown in the illustration.

The vase is a convex bowl ornamented with

medallions, scrolls and garlands and with violets or like flowers in oval panels.

The leading feature of the design is the flowers arranged within the oval panels in connection with the medallions, scrolls and garlands, all raised above the surface of the vase. 20
